METHOD OF CENTRIFUGALLY CASTING
LINERS IN BRAKE DRUM SHELLSWilliam D. Sargent, New York, N. Y., assignor,
by mesne assignments, to Durafer (Inc.),
Dover, Del., a corporation of Delaware

Application August 7, 1931, Serial No. 555,792

1 Claim. (Cl. 22—206)

The present invention relates to brake drums and a method of forming the same and embodies, more specifically, an improved composite brake drum construction having a cast iron liner and a malleable metallic shell, as well as an improved method of forming a brake drum of this character.

The advantages of cast iron as a braking surface are now recognized and a detail discussion thereof is not required herein. Suffice it to say that cast iron provides an excellent braking surface which is uniform in character and action and is far superior to steel. To provide the necessary strength in brake drums formed of cast iron, it has been necessary, however, to include such a quantity of metal in the spider or supporting structure for the drum that objectionable weight results.

Applicant has made exhaustive studies of brake drum structures formed of cast iron and of malleable metal such as sheet steel, and has found that the most serviceable form of brake drum is that in which a cast iron braking surface is used with a sheet steel shell. The problem of supporting the cast iron structure upon the light malleable metallic shell is one which has been very difficult of solution. In accordance with one brake drum construction covered in an application Serial Number 541,602 filed June 2, 1931, the malleable metallic shell is shrunk onto a pre-formed cast iron liner which has been cast by a centrifugal operation. The present invention relates to brake drums of similar construction but formed by casting the liner of iron directly into the malleable metallic shell.

The manifold advantages accruing from such construction will be readily apparent and an object of the present invention is, accordingly, to provide a method of forming a composite brake drum structure including a cast iron braking surface and a light malleable metallic supporting structure therefor.

A further object of the invention is to provide a method of forming a brake drum of the above character wherein an iron liner is cast directly into its malleable metallic supporting shell, such method including the centrifugal casting of the iron.

A further object of the invention is to provide a method of casting an iron liner centrifugally in a brake drum shell in such fashion that the liner is effectively engaged by the shell to prevent displacement thereof.

A further object of the invention is to provide a method of the above character wherein the dif-

ference in coefficient of expansion of cast iron and steel is utilized to provide a composite brake drum construction wherein an iron liner, cast into a malleable metallic shell, is maintained therein under radial compression.

The foregoing objects are attained specifically by a method including the preheating of sheet steel shells and centrifugally casting into the preheated shell, a sufficient quantity of iron to form a liner therefor. Upon pouring of the iron into the rotating shell, the temperature of the iron and shell will reach a common value, from which value further cooling of the liner and shell causes the shell to compress the liner by reason of the greater coefficient of expansion of the sheet steel shell as compared to that of the cast iron liner.

A further object of the invention is to provide a composite brake drum structure including a cast-iron liner effectively engaged by a sheet steel shell.

A further object of the invention is to provide a composite brake drum construction including an iron liner cast centrifugally into a supporting shell, means being provided to prevent extrusion of the metal of the liner.

A further object of the invention is to provide a brake drum construction of the above character wherein the iron liner is cast centrifugally directly in the shell.

A further object of the invention is to provide an improved machine for centrifugally casting iron liners in malleable metallic shells.

Further objects of the invention, not specifically enumerated above, will be apparent in connection with the accompanying description wherein reference is made to the accompanying drawings, in which:

Figure 1 is a view in vertical section, taken through a machine constructed in accordance with the present invention, and showing a shell which is ready for the casting operation.

Figure 2 is a detailed view in section showing a modified form of shell.

Figure 3 is a detailed view in section, similar to Figure 2, showing the manner in which one form of brake drum shell is adapted for the casting operation to prevent extrusion of the metal of the liner.

Figure 4 is a view in section, similar to Figure 1 showing a modified machine for casting composite brake drums in accordance with the present invention.

Referring particularly to Figure 1, a foundation for a casting machine is shown at 10 and 55

formed with a recess 11 in which an electric motor 12 or other suitable power source is received. A rim 13 may be formed about the recess to provide a mounting for a standard 14 upon which a manually operated lever 15 is pivoted. Spring 16 normally urges the lever into the position shown in Figure 1 and a stop 17 limits such movement.

A power shaft 18 of the motor 12 carries a sleeve 19 which is secured thereto by means of a set screw 20. Sleeve 19 is formed with a horizontal table 21 upon which bosses 22 are formed. Sleeve 23, coaxially with the shaft 18, serves as a centering means for the shell and pouring plate, described hereinafter.

A pin or pins 25 are provided on the table 21 to afford an effective driving connection between the table and a brake drum shell 26. The shell 26 is preferably provided with a cylindrical flange 27 which is adapted to engage, snugly, the exterior surface of sleeve 23. Recesses 28 are also provided in the shell 26 to facilitate the securing of the shell to an appropriate wheel and these recesses are utilized as recesses within which the driving pins 25 engage.

If desirable, a convenient means may be provided for elevating the shell from the table 21 after the casting operation has been completed. To afford such means, a plurality of lifter rods 29 are slidably mounted in the table 21. Collars 30 on these rods limit the downward movement thereof and the upward extremities of the rods engage a cooperating surface of the shells 26. An annular carrier 31 is suitably connected to the lower extremity of the rods 29, the carrier serving as a track against which rollers 32 engage to elevate the rods 29 simultaneously. Rollers 32 are journaled upon the extremities of arms 33 which form a forked extremity upon lever 15. Obviously, this lifting mechanism may be dispensed with without departing from the scope of the invention.

Within the sleeve 23, the hub 35 of a pouring plate 34 is received, the pouring plate being formed with an upper concave surface 36 upon which the metal is poured. Any suitable means may be provided to secure the pouring plate 34 effectively within the recesses formed by the sleeve 23.

While it is recognized that a number of ways of securing the pouring plate in such position may be utilized, the structure shown herein includes a solenoid or electromagnet 38 which may be conveniently energized when the pouring plate 34 is placed in position within the sleeve 23. Slip rings and brushes may be utilized to transmit current from a suitable source to the rotating magnet and, in as much as this specific structure forms no part of the present invention, a detailed description thereof will not be made herein.

To facilitate movement of the pouring plate the standard 14 is provided with spaced arms 65 in which a shaft 66 is journaled. Spaced collars 67 are pinned to the shaft and spring 68 engages the lower collar to urge the shaft 66 normally upwardly. A sleeve 69 is journaled on the shaft between the collars 67 and is formed with a pin or pins 70 engaged by the slotted extremity 71 of a lever 72. The end of lever 72 is pivoted on the standard 14 at 73 and link 74 is pivoted on the lever 72 at 75. The lower end of arm 74 is pivoted at 76 to a lever 77 which is provided with a treadle 78 and is pivoted at 79 upon the standard 14. To depress the pouring plate and position the same preparatory to pouring, the trea-

ble 78 is depressed and subsequent energization of the magnet 38 maintains the plate in pouring position.

It will be seen that the shell 26 is formed with a dust guard 39 and a lip 40 which extends inwardly from the adjacent liner supporting portion of the shell to prevent extrusion of the metal from the shell. A modified form of shell is shown in Figure 2, the liners within the shells shown in Figures 1 and 2 being indicated by a dot and 10 dash line. It will thus be seen that the lip 40 effectively prevents extrusion of the metal of the liner from the shell. It may be preferable to form the shell with a circumferential channel or channels therein in order that the iron, when 15 cast, may flow into such channels and increase the area of contact between the shell and iron. In the forms shown, these channels are curved in Figure 1, tapering in depth in Figure 2, and curved with a width substantially less than the width 20 of the shell in Figure 3. The specific form of channel, however, constitutes no part of the invention and it will be readily seen that channels of varying width and depth may be formed in the shell without departing from the scope of the 25 present invention.

In Figure 3 means is shown for facilitating the casting of iron liners within shells which are not formed with lips to prevent extrusion of the metal. In this construction, a ring 41 is provided with a 30 cylindrical flange 42 which is adapted to engage within the adjacent shell portion. Screws 43 enable the ring to be secured to the shell by engagement with the dust guard 39 thereof. The casting of the iron liner within the shell shown 35 in Figure 4 results in a liner having an interior surface indicated by the dot and dash line.

In the construction shown in Figure 4 the rim 13 receives a standard 44 in place of the bracket 14. The motor, rotating table, and shell elevating mechanism are similar to the corresponding elements described in connection with Figures 1 and 2. Instead of positioning the pouring plate by means beneath the table 21, the plate is centered by a mechanism carried by the standard 44. 45

To this end, a pouring plate 45 is provided having a centering cone 46 upon its hub 47. The pouring plate is formed with an upper concave pouring surface 48 and the stabilizing legs 49, as described in connection with Figures 1 and 2. A 50 vertically slideable shaft 50 is mounted upon the pouring plate 45 and is journaled within bearings 51, formed upon an extension 52 of the standard 44. Collars 53 are secured to the shaft 50 and spring 54 normally urges the shaft 50 and pouring 55 plate 45 into the position shown in Figure 5. A sleeve 55 is journaled upon the shaft 50, between the collars 53 and carries a pin or pins 56 which are engaged by the slotted extremity 57 of a lever 58 which is pivoted at 59 upon an extension 60 60 of the standard 44. The other end of lever 58 is connected to a rod 61 which is pivoted intermediate the ends of a treadle lever 62 which is pivoted upon the standard 44 at 63.

It will thus be seen that spring 54 urges the 65 centering cone 46 into a cooperating conical socket 64, formed in the table 21, and the sleeve 27 on the drum 26 engages the hub 47 to be centered thereby. Initial movement of the lever 62 elevates the pouring plate from the shell 26 and 70 then engages the extremity of lever 15. Continued movement of the lever 62 elevates the shell 26 and the latter is thus cleared from the table 21 and may be conveniently displaced therefrom.

The foregoing mechanism thus provides a con- 75

venient apparatus by which the centrifugal casting operation is effected, the pouring plate serving to distribute the metal effectively within the shell 26 and also to center the shell and clamp the elements in pouring position.

The thickness of the cast iron liner may be determined either by forming a lip on the steel drum or by providing a suitable temporary lip or flange for the casting operation, such flange being removed upon completion thereof.

It has been found that the composite drum structure is more serviceable if the casting operation includes the preheating of the shell before the pouring of the iron thereinto. To this end, the shell is heated preferably to a temperature between 500 and 1200°, after which the iron is poured thereinto during rotation of the shell. After pouring, the iron of the liner and the metal of the shell reach substantially the same temperature, upon further cooling from which temperature the metal of the shell shrinks at least

as much as the iron of the liner to preserve an intimate contact therebetween. In reality, the iron of the liner is compressed by the metal of the shell and is thus effectively secured therein. In this fashion, a thin steel shell, having the desired strength, is formed with a braking surface of excellent character and wearing qualities and the structure is such that the two metals are permanently secured together.

While the invention has been described with specific reference to the construction shown in the accompanying drawings, it is not to be limited, save as defined in the appended claim.

I claim as my invention:

The method of casting centrifugally comprising preheating a comparatively thin shell to a temperature between 500 and 1200 degrees Fahrenheit, rotating the shell upon a vertical axis, and pouring metal thereinto.

WILLIAM D. SARGENT. 20
